UNITED STATES PATENT OFFICE.

CORNELIUS B. CORCORAN, DECEASED, LATE OF NEW YORK, N. Y.; BY MICHAEL J. CORCORAN, OF NEW YORK, N. Y., ADMINISTRATOR, ASSIGNOR TO UNDERWOOD TYPEWRITER COMPANY, OF NEW YORK, N. Y., A CORPORATION OF DELAWARE

TYPEWRITING MACHINE.

Application filed July 21, 1923. Serial No. 653,041.

To all whom it may concern:

Be it known that CORNELIUS B. CORCORAN, deceased, late a citizen of the United States, and late residing in the borough of Bronx,

5 county of Bronx, city and State of New York, invented certain new and useful Improvements in Typewriting Machines, of which the following is a specification.

This invention relates to sound-deadening 10 devices for typewriting machines, and more particularly to a canopy that can be fastened to a machine so as to move transversely thereof, and to deaden the noises produced by the types and the carriage.

15 The body of the canopy is preferably oblong of a size sufficient to cover the carriage from end to end and from the rear to a point over the forward edge of the platen, and is so curved or bent in section from 20 front to rear that its front edge is brought low enough to rest upon the end plates of the carriage when the canopy is in closed position.

The body of the canopy is properly composed of inner and outer shells constructed 25 preferably of light sheet-metal, the inner shell being profusely perforated to permit the functioning of a pad or filler of any suitable sound-deadening or absorbing material, such as felt, which is held between 30 the shells.

The position of the canopy, when it is superimposed over the carriage, is such that it might interfere with the placing of work 35 in the machine, and to relieve this condition suitable brackets, in which the canopy is pivotally hinged, are fastened to the end members of the carriage-frame, so that the canopy may be swung upwardly and backwardly to give free access to the carriage. The canopy brackets have suitable projections 40 on their main body portions that act as stops to hold the canopy in an upright position when work is being placed in the machine, and to prevent it from swinging down against the rear of the machine. To further hold the canopy or cover away from the machine, and also to prevent movement or "chattering" when the canopy is down, 45 screw members, which form the pivot at each rear corner of the canopy, are provided with spring washers which tend to check

any undesired movement of the canopy without detracting in any way from the pivotal action of the joint.

To eliminate possible noise when the canopy is closed to begin typing, the two forward corners are provided with bumpers, made of a suitable sound-deadening material, such as rubber, which are fastened in position by means of ears or clamping members depending from and integral with the outer shell of the canopy.

Other features and advantages will hereinafter appear.

In the accompanying drawings,

Figure 1 is a side elevation of a typewriting machine that has been placed inside of a sound-deadening shoe, and shows the sound-deadening canopy, described and claimed herein, mounted on the carriage of the machine.

Figure 2 is a side elevation of the sound-deadening canopy in raised position, and shows the method of fastening the canopy to the carriage.

Figure 3 is a plan view of the sound-deadening canopy mounted on a typewriting machine, the carriage of which has been moved transversely to an extreme position at one side of the machine.

Figure 4 is a partial sectional rear view of the sound-deadening canopy, showing in detail the construction of its rear edge and of the pivotal joint.

Figure 5 is a detail perspective view of one of the forward corners of the sound-deadening canopy, showing the method of fastening the bumpers in place thereon.

When a typewriting machine is being used in doing work, a large part of the objectional noise produced is made by the type-heads striking against a platen 6, and by the shifting of a platen-frame 7 in a carriage 8 which is mounted to move transversely on a rail 9, which is supported by a bracket 10 which is part of a frame 11 of the machine. Some of this noise may be deadened by enclosing the frame 11 of the machine in such a sound-deadening device as a shoe 12, or the frame 11 may have sound-deadening devices built into it as an integral part thereof.

Such sound-deadening devices or means, however, will not wholly dampen the sound

waves emanating upwardly and away from the machine, and especially those sound waves set in motion by the striking of the platen 6, and the shifting of the platen-frame 7, which were referred to above. To effectively deaden these noises a sound-deadening canopy 13 composed of an outer shell 14 and an inner closely perforated shell 15, with a pad of sound-deadening material 16 fixed therebetween, is superimposed directly over the carriage 8.

Clamped in the turned-over rear edge of the inner shell 15, and held in place by means of screws 17, is a bar 18 which has its ends bent down to form ears 19. The ears 19 are provided with tapped holes 20 to receive screws 21, which, by means of their construction, form a pivotal connection between the canopy 13 and brackets 22. The brackets 22 are fastened to the ends of the carriage 8 in such a manner that the canopy 13 will move transversely of the machine with the carriage 8 and so remain superimposed directly over it at all times. The brackets 22 are provided with projecting stop portions 23 near their rear ends which provide stops or rests to hold the canopy 13 in an upright position when it is raised to place work in the machine, and to prevent it from swinging down against the rear of the machine. To further hold the canopy 13 in an upright position and also to prevent unintentional movement or "chattering" when it is closed, the screws 21 are provided with spring washers 24, which tend to tighten the joint between the canopy 13 and the brackets 22 without in any way detracting from the pivotal action of the connection.

To prevent any possible noise being produced by the front edge of the canopy 13 striking the end cover-plates of the carriage 8, the front corners of the canopy 13 are provided with bumpers 25 which have their projecting hub portions 26 clamped under depending clips 27 which are bent downward from the outer shell 14 of which they are an integral part.

The usual side gages 28 for the work-sheet are slidable from left to right along a horizontal supporting rod 29, to which they are usually hinged. This rod may be fixed or supported by its ends in the same brackets 22 which carry the canopy 13.

Variations may be resorted to within the scope of the invention, and portions of the improvements may be used without others.

Having thus described my invention, I claim:

1. In a typewriting machine, the combination with a platen and a carriage therefor, of a sound-deadening and sound-absorbing canopy placed over and above the carriage and platen, said canopy including a foraminous sheet placed next to the carriage and platen, and a sheet of sound-ab-

sorbing material extended over the back of the foraminous sheet, the latter designed and intended to have the sound waves propagated by the typewriting machine strike thereon and be broken up thereby and the sheet of sound-absorbing material absorb any of said sounds that may reach it, whereby the sounds emanating from the typewriting machine that reach the canopy will be broken up, deadened and absorbed. 75

2. In a typewriting machine, in combination, a sound-deadening canopy, means for pivotally attaching said sound-deadening canopy so that it is movable transversely of the machine from one side to the other, means to hold said sound-deadening canopy in an upright position when said sound-deadening canopy is raised to permit the placing of work in the machine, means to prevent any unintentional movement or "chattering" of said sound-deadening canopy while in either a raised or lowered position, and means to prevent noise being emitted when the forward edge of said sound-deadening canopy comes in contact with the machine when said sound-deadening canopy is lowered into position.

3. In a typewriting machine, in combination, a sound-deadening shoe or other similar device in which the machine may be placed, a movable carriage, a sound-deadening canopy superimposed over said movable carriage, means for pivotally attaching said sound-deadening canopy to said movable carriage to permit moving said sound-deadening canopy and said movable carriage together transversely of the machine from one side to the other, means to hold said sound-deadening canopy in an upright position when said sound-deadening canopy is raised to permit the placing of work in the machine, means to prevent any unintentional movement or "chattering" of said sound-deadening canopy when in either a raised or lowered position, and means to prevent noise being emitted when the forward edge of said sound-deadening canopy comes in contact with said movable carriage when said sound-deadening canopy is lowered into position. 105

4. In a typewriting machine, in combination, a sound-deadening shoe or other similar device in which the machine may be placed, a movable carriage, a sound-deadening canopy superimposed over said movable carriage, and means for pivotally connecting said sound-deadening canopy to said movable carriage to permit moving said sound-deadening canopy and said movable carriage together transversely of the machine from one side to the other. 120

5. In a typewriting machine having sound-deadening devices built into the frame thereof, in combination, a movable carriage, a sound-deadening canopy superimposed over 130

said movable carriage, means for pivotally attaching said sound-deadening canopy to said movable carriage to permit moving said carriage together transversely of the machine from one side to the other, means to hold said sound-deadening canopy in an upright position when said sound-deadening canopy is raised to permit the placing of work in the machine, means to prevent any unintentional movement or "chattering" of said sound-deadening canopy when in either a raised or lowered position, and means to prevent noise being emitted when the forward edge of said sound-deadening canopy comes in contact with said movable carriage when said sound-deadening canopy is lowered into position.

6. In a typewriting machine, the combination of a platen, a carriage therefor, and a canopy mounted on the carriage over the platen and extending to the rear of the carriage, said canopy having a sound-absorbing pad on its under face and overhanging the ends of the carriage and absorbent of sound arising from the platen and carriage ends, and also from the rear of the carriage.

7. In a typewriting machine, the combination of a platen, a carriage therefor, and a canopy over the platen and extending to the rear of the carriage, and there hinged to the carriage, to swing up and back from the platen, said canopy having a sound-absorbing pad on its under face.

8. In a typewriting machine, the combination of a platen, a carriage therefor, and a canopy mounted on the carriage over the platen and extending to the rear of the carriage, said canopy having a sound-absorbing pad on its under face and overhanging the ends of the carriage and absorbent of sound arising from the platen and carriage ends, and also from the rear of the carriage, said canopy hinged at its rear to said carriage to swing back and off of the platen and carriage.

9. In a typewriting machine, the combination of a platen, a carriage therefor, a canopy over the platen and extending to the rear of the carriage, said canopy having a sound-absorbing pad on its under face and overhanging the ends of the carriage and absorbent of sound arising from the platen and carriage ends, and also from the rear of the carriage, supports extending rearwardly from said carriage, and means hinging said canopy upon said supports, and affording a clearance space in rear of the car-

riage and in front of the hinge for the downward passage of work-sheets. 60

10. In a typewriting machine, the combination of a platen, a carriage therefor, a canopy over the platen and extending to the rear of the carriage, and there hinged to the carriage, to swing up and back from the platen, said canopy having a sound-absorbing pad on its under face, and cushioning means supporting said canopy at its front upon the ends of said carriage. 65

11. A sound-absorbing sheet forming part 70 of a quieting device for typewriters, comprising two metal sheets and an intervening sheet of sound-absorbing fabric, the inner of said sheets being foraminated, for the purpose specified. 75

12. In combination, a typewriting machine having a platen and a framework, a sound-subduing pack fastened upon said framework, a canopy having a sound-subduing pad overhanging the platen and extending rearwardly of said pack, and means hinging said canopy at its rear end upon said machine to enable it to swing up and off from the platen. 80

13. In combination, a typewriting machine having a platen and a framework, a sound-subduing pack fastened upon said framework, a canopy having a sound-subduing pad overhanging the platen and extending rearwardly of said pack, and means 90 hinging said canopy at its rear end upon said machine to enable it to swing up and off from the platen, a passage being left between the platen and said hinge for a work-sheet to hang back of said pack. 95

14. The combination with the frame, carriage and platen of a typewriting machine, of sound-subduing means including a sound-deadening pack open at its top and fixed on the frame of the machine and having side 100 walls and rear walls, all of said walls lined with sound-deadening material, and a sound-deadening carriage-canopy lined with sound-deadening material and mounted on the carriage to travel therewith and largely covering the top opening of the pack and co-operative with the sound-deadening walls of the pack to form an air-pocket to confine, break up, deaden and absorb the sounds arising from the operation of the machine; said 110 canopy mounted for movement from over the platen, to give access to the paper thereon. 105
